UNITED STATES PATENT OFFICE

136,552

DESIGN FOR A WASHING MACHINE OR SIMILAR ARTICLE

Edward L. Miller, Moline, Ill., assignor to American Machine and Metals, Inc., New York, N. Y., a corporation of Delaware

Application August 5, 1943, Serial No. 110,846

Term of patent 7 years

To all whom it may concern:

Be it known that I, Edward L. Miller, a citizen of the United States and a resident of Moline, in the county of Rock Island and State of Illinois, have invented a new, original, and ornamental Design for Washing Machines or Similar Articles, of which the following is a specification, reference being had to the accompanying drawings, forming part thereof.

Figure 1 is a front perspective view of a washing machine or similar article, showing my new design;

I claim:

The ornamental design for a washing machine or similar article, as shown.

EDWARD L. MILLER.
